ATTORNEY

UNITED STATES PATENT OFFICE.

SAMUEL E. HUNTING, OF SAN FRANCISCO, CALIFORNIA.

PUMP.

Application filed August 11, 1921. Serial No. 491,457.

To all whom it may concern:

Be it known that SAMUEL E. HUNTING, a citizen of the United States of America, residing at San Francisco, in the county of

5 San Francisco and State of California, has invented certain new and useful Improvements in Pumps, of which the following is a specification.

The present invention is an improved 10 pump mechanism and relates to apparatus for operating a deep well cylinder which apparatus is variously termed deep well pumping head, working head or pumping jack.

15 One object of my invention is to provide a pump structure wherein side thrust or bending strain will be minimized in pump structures wherein a pump rod is reciprocated by a crank.

20 Another object is to lessen the shock to the pump mechanism due to the change of direction of the stroke.

Another object is to provide a pump mechanism which will permit the plunger of the 25 pump to be drawn up through the well pipe without removal of said pump mechanism.

Another object is to so connect the driving gears on a common shaft that they will function independently of each other.

30 Another object is to provide bracing supports for the bedplate supporting the crank shafts which supports will have strength and rigidity and will be inexpensive to construct.

35 Other objects and advantages, such as structural details, making for durability and strength and efficiency in operation, and economy in construction, will appear as this description proceeds.

40 In these specifications and the annexed drawings, the invention is illustrated in the form considered to be the best, but it is to be understood that the invention is not limited to such form, because it may be embodied in other forms, and it is also to be understood that in and by the claims following the description it is desired to cover the invention in whatever form it may be embodied.

45 In the accompanying two sheets of drawings, Fig. 1 is side elevation, partly in section, of my improved pump mechanism.

Fig. 2 is a top plan view of Fig. 1 in full lines.

50 Fig. 3 is a detail partly in section showing my differential driving gear.

Fig. 4 is a fragmentary view, partly in section, of the lower end of a connecting rod, with its bearing, and showing an oil reservoir therein.

55 Figs. 5, 6, 7, 8 and 9 are perspective views respectively of a floor plate, including an annular flange member, pump T, bed plate, and packing gland, and packing gland bushing, the figures being placed one above another to simulate the order of assembly and explain the relation of each to the others.

Fig. 10 is a detail of a fragment of casting showing means for engaging a bolt-head.

70 Fig. 11 is a central section of a turn buckle means.

75 Referring to the drawings, Fig. 1, the numeral 1 indicates a foundation plate (also shown in perspective in Fig. 5).

At 2 I show an annular flange member having a depending flange 3 adapted to engage a hole in the foundation plate 1.

At 4 I show a pump T provided with a bottom flange 6 adapted to overlie the flange 2. A gasket 7 is placed between flanges 2 and 6.

80 A flange 8 on the upper end of T 4 fits against the lower face of a bed plate 9 shown in Fig. 7.

85 The bed plate 9 has a bore 11 registering with that of the T 4. The bed plate casting is provided with a web or flange 12 in which are bolt holes 13. Bolts are extended upwardly through these holes to secure to the bed plate a flange 14 on an upstanding pumprod guide 16, the upper end 17 of which forms part of a stuffing box, the other part of which is indicated at 18.

90 The bed plate 9 is secured and braced to the foundation plate 1 by stay bolts 19 which are surrounded by pipes 21 and 22 connected by sleeves or turnbuckles 23 as shown in detail, Fig. 11.

95 The heads of bolts 19 are inserted laterally through openings in lugs 26 shown in Fig. 7 and in detail in Fig. 10. The lower ends of bolts 19 extend through holes 27 in flanges 28 in foundation plate 1 and are secured by nuts 29, Fig. 1.

100 This structure permits of a limited vertical adjustment of the bed plate by means of turnbuckles 23 which space the bed plate from the foundation plate.

110 Power is applied to my pump through a belt pulley 31, Fig. 1, secured to a drive shaft 32 journaled in a bearing 33 integrally

formed in bed plate 9. Secured on shaft 32 are pinions 34 and 36, Fig. 2, which mesh with and drive gear wheels 37 and 38 on opposite sides of bed plate 9. These gear 5 wheels 37 and 38 are differentially driven on a shaft 39 in a bearing 41 in bed plate 9, Fig. 7.

The differential drive is shown in detail in Fig. 3. The purpose of driving the gears 10 37 and 38 independently is to divide the load evenly at all times between these gears and between two similar gears 42 and 43 in mesh therewith and also journaled differentially in a bearing 44 in bed plate 9.

15 The pump rod (to be later described) is driven by connecting rods indicated at 46 and 73, four in number, two being on each side of the bed plate, and each driven by a gear 37, 38, 42 and 43. Each of these 20 gears is provided on the spokes thereof with means for engaging crank bearings, said means (indicated at 47) diametrically spaced to afford an adjustment for different lengths of working stroke.

25 In order to divide the strain of drive equally between the gears, and taking into consideration inequalities of the teeth thereof due to wear or imperfect formation, I secure the gears on hollow shafts extending 30 half way through the bearings on bed plate 9 at 48, in Fig. 3, which surround shaft 39 and are rotatable thereon.

The gears with hollow shafts attached are secured on shafts 39 by washers 49 held in 35 place by bolts 51.

The gear bearing 52 is provided with an oil well 53 from which oil is fed by capillary attraction through a groove 54 by a wick 56.

40 In Fig. 4 at 57, I show a crank bolt which extends through any of the apertures 47, in the gears 37, 38, 42 or 43. This bolt is surrounded by a bronze metal bushing 58. I place a wick in a groove 61. The wick draws 45 oil from a well 62 in a casting 63, through which extends the bolt 57 and bearing 58, which are secured by a washer 64 and nut 66.

The crank castings 63 are operatively connected to a cross-head 67 by the bolts or connecting rods, 46 and tubular members 73.

50 The head of each bolt 46 is inserted in a T shaped passage as indicated at 68, Fig. 4. The upper part of this passage is of a size sufficient to allow the entrance of the body of 55 the bolt and the lower part admits the head of the bolt. When the parts are thus assembled, the upper ends of bolts 46 are extended through shafts 69 journaled in bearings in the cross-head 67, and secured by nuts 71 60 and lock nuts 72.

Tubular members 73 surround the bolts 46 and bear at one end against the castings 63 and at the opposite end against shafts 69. This structure forms tubular braces for the 65 connecting rods 46 and assures equality of

length of said rods, and at the same time provides an operative connection of the cross-head with the driving elements which is readily and easily assembled or dismembered.

70 The cross-head 67 is provided with a horizontal web 74 which strengthens the casting and forms a floor on which are cast oil wells 76 serving the bearings for shafts 69.

The web is centrally bored to admit a 75 bushing 77 internally threaded to engage the threaded end of the pump rod 78.

The threads on pump rod 78 extend downwardly to a point 79 at which point adjusting nuts 81 support a washer 82 against 80 which presses one end of a spring 83, the opposite end of which presses against a washer 84 bearing against the underside of web 74.

A washer 86 bears against the upper side 85 of web 74 and a spring 87 bears against this washer at one end, and at the other against a washer 88 secured by adjusting nuts 89 threaded on the upper end of pump rod 78.

90 This structure permits a certain amount of movement of the cross-head up or down, independently of the pump rod. The web 74 slides on bushing 77 as either of springs 83 or 87 are compressed.

The opposed springs alternately absorb 95 the shock incidental to the change of direction of the stroke and increase the working capacity and durability of the pump.

It will be seen that by unscrewing nuts 89 from pump rod 78, and unbolting flange 14 100 on the base of the stuffing box from the bed plate, the cross-head may be readily disengaged from the pump rod, the flange remaining on the pump rod. The cross-head and connecting rods may be moved aside as indicated in dotted lines in Fig. 1 and the pump rod and any parts attached thereto may be withdrawn as a unit without disconnecting the cross-head from the drive elements.

105 The distinct advantages of my pump may be summed up as follows:

The use of four differentially driven gears which act as or drive cranks, so arranged that the side thrusts of said cranks are counterbalanced;

110 The use of a horizontal bed plate, which is braced to the foundation at a right angle, instead of a diagonal bracing incidental to vertical type pumps, and placing the brace supports directly under the bearings of the crank shafts so that all working strain shall be transmitted directly through the bed plate to the foundation, without producing bending strain on the bed plate;

115 The use of opposed springs in the connection between the pump rod and cross-head to absorb shock in the mechanism due to change of direction of stroke.

120 The use of adjustable braces between the foundation and bed plate and means for 130

drawing bed plate and foundation together against these braces;

5 The provision, in a pump mechanism, of differentially driven counter balanced reciprocating members for the pump rod, a guide for said pump rod, and means whereby the reciprocating members may be folded aside to permit the withdrawal of the pump rod and attached parts.

10 I claim:

1. In a pump mechanism, a cross head and a pump rod adapted to be reciprocated by four connecting rods, and four cranks adapted to drive said connecting rods.

15 2. In a pump mechanism, a cross head and a pump rod adapted to be reciprocated by four connecting rods, and four cranks adapted to drive said connecting rods, said cranks being parts of wheels journalled in

20 a horizontally positioned bed plate.

25 3. In a pump mechanism, a cross head and a pump rod adapted to be reciprocated by four connecting rods, and four cranks adapted to drive said connecting rods, said

30 cranks being parts of wheels journalled in a horizontally positioned bed plate, driving means for said cranks including said wheels, and further comprising a train of gears, said train consisting of one driving gear and two driven gears, said driven gears having the same number of teeth.

35 4. In a pump mechanism, a cross head and a pump rod adapted to be reciprocated by four connecting rods, and four cranks adapted to drive said connecting rods, said cranks being parts of wheels journalled in a horizontally positioned bed plate, driving means for said cranks including said wheels, and further comprising a train of

40 gears on each side of said bed plate, each train consisting of one driving gear and two driven gears all of said driven gears having the same number of teeth.

45 5. In a pump mechanism, a cross head and a pump rod adapted to be reciprocated by four connecting rods, and four cranks adapted to drive said connecting rods, said cranks being parts of wheels journalled in a horizontally positioned bed plate, driving

50 means for said cranks including said wheels, and further comprising a train of gears on each side of said bed plate, each train consisting of one driving gear and two driven gears all of said driven gears having the same number of teeth, opposite driven gears being differentially connected on a common shaft so that each will be independent as to reciprocating the said cross head.

55 6. In a pump mechanism, a cross head and a pump rod adapted to be reciprocated by four

connecting rods, and four cranks adapted to drive said connecting rods, said cranks being parts of wheels journalled in a horizontally positioned bed plate, a foundation plate, brace supports between said bed plate and said foundation plate, whereby the working strains of the mechanism are transmitted directly to the foundation plate, said brace supports consisting of rigid spacing members adapted to space the bed plate from the foundation plate and threaded members adapted to draw plate and said foundation plate together against the said spacing members driving means for said cranks including said wheels, and further comprising a train of gears on each side of said bed plate, each train consisting of one driving gear and two driven gears all of said driven gears having the same number of teeth.

7. In a pump mechanism, a cross-head and a pump rod adapted to be reciprocated by four connecting rods, and four cranks adapted to drive said connecting rods, said cranks being parts of wheels journalled in a horizontally positioned bed plate, driving means for said cranks including said wheels, and further comprising a train of gears on each side of said bed plate each train consisting of one driving gear and two driven gears all of said driven gears having the same number of teeth, a foundation plate, a discharge T, or pump part positioned between said bed plate and said foundation plate and held securely in place by threaded members adapted to draw said bed plate toward said foundation plate, spacing members adapted to space the bed plate from the foundation plate and provided with turn buckle means whereby they can be expanded to form rigid bracing between said plates.

8. A pump mechanism comprising a pump rod, driving gears disposed about said rod in quadrilateral arrangement, and connecting rods adapted to transmit motion from said gears to said rod.

9. In a pump mechanism wherein a pump rod and cross head are reciprocated by connecting rods raised and lowered by cranks driven by gears quadrilaterally positioned around said pump rod, a guide for said pump rod centrally positioned within said quadrilateral, said guide adapted to be withdrawn with said pump rod and means whereby the said reciprocating members may be folded aside and the guide withdrawn with the pump rod.

In testimony whereof I affix my signature.

SAMUEL E. HUNTING.
